UNITED STATES PATENT OFFICE.

GENERO SO COMPECK, OF NEWARK, NEW JERSEY.

DESIGN FOR AN UMBRELLA ATTACHMENT.

53,437.

Specification for Design. Patented June 17, 1919.

Application filed January 18, 1919. Serial No. 271,929. Term of patent 7 years.

To all whom it may concern:

Be it known that I, GENEROSO COMPECK, a citizen of the United States, residing at Newark, in the county of Essex and State of New Jersey, have invented a new, original, and ornamental Design for Umbrella Attachments, of which the following is a specification, reference being had to the accompanying drawing, forming a part thereof.

The figure is a perspective view of an umbrella attachment, showing my new design.

I claim:

The ornamental design for an umbrella attachment, as shown.

GENERO SO COMPECK.

Witnesses:

A. P. COMPECK,
PAUL W. COMPECK.
